UNITED STATES PATENT OFFICE.

JOHN P. SAUERWALD, OF BALTIMORE, MARYLAND.

NECKTIE-ROLL.

1,113,055.

Specification of Letters Patent.

Patented Oct. 6, 1914.

Application filed January 5, 1914. Serial No. 810,491.

To all whom it may concern:

Be it known that I, JOHN P. SAUERWALD, a citizen of the United States, residing at Baltimore, in the State of Maryland, have invented new and useful Improvements in Necktie-Rolls, of which the following is a specification.

This invention relates to an improved pressing device, and has for an object to provide a device on which may be rolled neck-ties and like articles, for the purpose of pressing the same and removing creases therefrom.

Other objects of this invention are to provide an economical, easily operated device, simple and strong in construction and light in weight so that the device may be easily handled, will take up but little space, and may be readily carried about in traveling.

Further objects and advantages of this invention will be brought out in the following detailed description of the present embodiment thereof, the same being shown in the accompanying drawings in which—

Figure 1 is a perspective view of the pressing device having a necktie mounted thereon. Fig. 2 is a longitudinal central section through the device, the dotted lines showing the position of the rolled necktie thereon. Fig. 3 is a transverse section through the handle of the device taken on the line 3—3 of Fig. 2, showing the outer clip supporting ring. Fig. 4 is a transverse section through the device on the line 4—4 of Fig. 2, showing the ratchet ring and the pawl adapted to interlock therewith upon the rotation of the ring in one direction.

Referring to these drawings, wherein like characters of reference designate similar parts throughout the several views, 10 designates a handle provided at one end with a tubular or barrel portion 11 slightly reduced in diameter from that of the handle, to provide a shoulder 12 at the inner end of the barrel 11. In the inner end of the barrel 11 a bearing 13 is located receiving the inner end of a spindle 14 which extends throughout the entire length of the barrel 11 and is provided with a cap or disk 15 closing the open end of the barrel and bearing thereagainst. A spring 16 is mounted in the barrel 11 about the spindle 14, has one end secured to the bearing 13 and has its opposite end secured to the outer end of the spindle 14. Upon rotation of the spindle

14 the spring 16 is wound, and upon release of the spindle the latter is returned to normal position by the tension of the spring 16. Detachably mounted upon the cap or disk 15 is a cylinder 17, the same inclosing the barrel 11 and engaging slightly over the body of the handle 10 beyond the shoulder 12, the latter providing a bearing for the inner end of the cylinder 17. The outer end of the cylinder is provided with an inwardly extending annular flange 18, the inner edge of which closely fits against the barrel 11. The barrel 11 is provided with a detachable collar or shoulder 19 upon its outer end adapted to engage the flange 18 and retain the cylinder 17 in position about the barrel and to thereby hold the cap 15 and the spindle 14 in their respective positions. The inner end of the cylinder 17 is provided with a cup shaped ratchet ring 20 the same extending entirely around the inner wall of the cylinder 17 and having a flange portion engaging about the shoulder 12 to constitute a cylinder bearing to support the cylinder. The outer portion of the ring 20 is provided with a plurality of spaced apart openings 21 the edges of which constitute ratchet teeth for engagement against the out-turned end of a spring pawl 22 carried on the body of the handle. The body of the handle is recessed as at 23, at one side longitudinally of the handle within which is fitted for free movement the spring pawl 22. The spring pawl 22 is arched outwardly to provide a finger engaging part 24 adapted to be depressed to move the pawl 22 inwardly and release the same from the ring 20. A screw 25 or the like secures the inner end of the pawl 22 to the body of the handle as shown in Fig. 2.

It will be noted that the spindle 14 is secured to and turns with the cap 15, and that the cylinder 17 is secured to the cap 15 and turns as a unit with the same and the spindle 14. Also, the flange or collar 18 is fixed to the cylinder 17, and the flange or collar 19 is fixed to the barrel so that the cylinder and the parts carried thereby are securely held in position.

Mounted upon the cylinder 17 and extending substantially the entire length thereof is a clip or bail 26 comprising a substantially U-shaped piece having inturned arms 27 at its free ends engaging in outstanding bearings 28 carried upon the periphery of 110

the cylinder 17. Springs 29 are mounted upon the arms 27 and have their opposite ends bearing respectively upon the bail 26 and the outer surface of the cylinder 17 in such a manner as to yieldingly hold the bail 26 against the outer surface of the cylinder. The body of the handle 10 is provided near the shoulder 12 with an annular groove 30 in which is fitted a contracting spring ring 31, the free ends of which are turned outwardly and substantially radially to the ring to provide arms 32 adapted to abut and prevent the binding of the ring too tightly on the handle. These arms 32 have their free ends turned outwardly away from one another to provide supports or pins 34 upon which are hinged the inner ends of a second bail 33. The ring 31 is preferably made of yielding material whereby to normally urge the arms 32 toward one another, and the outturned ends of the arms 32 receive the eyes or overturned inner ends of the arms of the bail 33 which eyes are sprung over the pins 34 and bear frictionally against shoulder 36 to hold the bail 33 yieldingly in adjusted position. It will be understood that any suitable hinged connection may be had between the ring 31 and the bail 33 whereby the bail 33 may be held against the cylinder for a purpose hereinafter set forth, and at the same time admit of the swinging outwardly of the bail under sufficient pressure away from the cylinder.

35 In the operation of this pressing device the handle 10 is held stationary and the cylinder 17 turned thereabout to wind the spring 16 about the spindle 14. The spring pawl 22 is beveled at one side, as shown to advantage in Fig. 4, and slides freely over the ratchet ring 20, permitting of a free rotation of the cylinder 17 in winding up the spring 16. As soon as the spring 16 has been wound to the desired tension the spring pawl 22 engages in one of the openings 21 of the ring 20 and locks the cylinder 17 against retrograde movement. One end of a necktie 35, or like article, is placed flat upon the surface of the cylinder 17 beneath the bail or clip 26, the latter being first raised by the fingers from the cylinder. The springs 29 urge the bail 26 against the cylinder and thereby effect the clamping of the end of the tie beneath the clip. The operator now holds the opposite or free end of the tie with one hand and grasps the handle 10 in the opposite hand. The spring pawl 22 is now depressed when the spring 16 immediately rotates the cylinder 17 about the barrel 11 and effects the winding or rolling of the tie about the cylinder and upon itself as shown in Fig. 1. As the cylinder 17 turns under the action of the spring 16 it exerts considerable pull 65 on the tie and since the user of the device

holds the outer end of the tie, the tie is drawn taut and caused to roll or wind tightly about the cylinder. As soon as the necktie 35 is wound upon the cylinder the pawl 22 is released to hold the cylinder 70 from further turning. The ring 31 is turned around on the handle in the groove 30 until the bail or clip 33 is brought opposite to the outer end of the necktie 35. The bail 33 is now swung in against the free end of the tie to hold the tie from unwinding and in its taut position. The device may now be laid away for any desired length of time holding the tie in this position to effect the smoothing or pressing of 80 the tie and the removal of creases therefrom. If the tie, or other article to be pressed, is badly creased, the same may be dampened slightly before it is placed on the roller whereby to insure the smoothing of the tie 85 and the removal of the creases therefrom. When the tie is removed from the pressing device, the operator holds the handle 10, swings the outer clip or bail 33 away from the end of the tie 35 and pulls the tie to 90 unwind it from the cylinder 17. This operation turns the cylinder backward and again winds the spring 16, placing the device in condition to receive the next tie.

What is claimed is—

1. A stretching and pressing device for neckties and the like comprising a handle, a cylinder rotatable upon the handle, means for rotating the cylinder, a locking device on the handle engaging the cylinder to hold the same from rotation, a clip carried upon the cylinder for engagement with one end of a necktie, said locking device being adapted to be released whereby said cylinder rotates to wind the necktie thereon, and a 100 second clip carried on the handle for engagement with the outer end of the tie when wound.

2. A stretching and pressing device for neckties and the like comprising a handle having an extension, a cylinder rotatably mounted upon the extension, a spring having one end fixed to said extension and its opposite end secured to turn with the cylinder and adapted to be wound upon the rotation of the cylinder in one direction, a pawl on the handle engaging the cylinder to hold the same from turning when the spring is wound, a clip on the cylinder for engagement with one end of a necktie to hold it flat upon the cylinder, said pawl being adapted to be released from the cylinder whereby the latter is free to rotate and wind the necktie thereabout, and a second clip for engagement with the outer end of the necktie to hold the same flat and in wound position upon the cylinder.

3. In a stretching and pressing device as specified, a handle, a cylinder on the handle, a clip on the cylinder for engagement with 130

one end of an article to be pressed, means for rotating the cylinder, locking means for the cylinder to hold the same normally from rotation and adapted to be released to admit 5 the turning of the cylinder whereby to wind the article thereabout, and a second clip mounted for adjustment around the handle adapted to engage the free end of the article to hold the same in wound position 10 upon the cylinder.

4. A stretching and pressing device of the character described comprising a handle having a hollow barrel at one end, a spindle mounted for rotation in the barrel, a spring 15 encircling the spindle and having one end connected to the barrel and its opposite end connected to the spindle, a cap on the outer end of the spindle for closing said barrel, a cylinder mounted on said cap and extending inwardly about the barrel, means for retaining the cylinder and spindle in their 20 respective positions, a ratchet ring carried upon the cylinder, a finger operated pawl mounted upon the handle and normally engaging 25 said ratchet ring whereby to hold the cylinder from rotation, a clip secured against one side of the cylinder, and a second clip carried by the handle and adjustable thereabout for engagement with the free end of 30 an article wound upon the cylinder.

5. In a device of the character described, a cylinder, a support for the cylinder, a clip on the cylinder for engagement with one end 35 of an article, a spring secured at one end to the support and at its opposite end to turn with the cylinder for normally urging the cylinder for rotation in one direction whereby to wind the article on the cylinder, and a second clip on the support adapted for engagement 40 with the outer end of the article

to hold the same upon the cylinder when wound.

6. In a device of the character described, a cylinder, a support for the cylinder, a clip on the cylinder for engagement with one 45 end of an article, a spring secured at one end to the support and at its opposite end to turn with the cylinder and adapted to urge the cylinder for rotation in one direction whereby to wind the article about the cylinder, a second clip on the support adapted 50 for engagement with the outer end of the article to hold it to the cylinder, said article being adapted to be drawn from the cylinder against the tension of said spring 55 for removing the article, and a pawl on the support engaging the cylinder whereby to retain the same from retrograde movement upon the release of the article, and to maintain the cylinder in position to wind an article 60 thereon.

7. In a device of the character described, a cylinder, a support for the cylinder, a spring having one end fixed to the support and its opposite end secured to turn with 65 the cylinder for urging the cylinder for rotation in one direction, a pawl on the support engaging the cylinder to normally hold the same in position whereby said spring is placed under tension, an article engaging 70 clip on the cylinder, and a second clip on the holder adapted to engage the article when wound upon the cylinder.

In testimony whereof I have hereunto set my hand in presence of two subscribing witnesses. 75
